UNITED STATES PATENT OFFICE.

ERWIN R. STOEKLE, OF MILWAUKEE, WISCONSIN.

MEANS FOR VARYING THE ELECTRICAL IMPEDANCE OF A CIRCUIT.

Application filed November 24, 1924. Serial No. 751,911.

Method of and means for varying the electrical impedance of a circuit.

This invention relates to an improved method and means for varying the electrical impedance of a circuit particularly for varying the so-called reactive or inductive component of said impedance.

In electrical circuits, especially of the type employed in radio communication it is often desirable to adjust the relation between the inductance and the resistance of a circuit with great accuracy. For example the conditions under which a vacuum tube will oscillate is governed by the relation established between the external and the internal impedance of the tube. The condition for self-oscillation of the tube is usually expressed by stating that the inductance in the plate circuit of the tube must be sufficient to effect complete neutralization of the circuit resistance. Although the devices to be herein described are particularly adapted to the control of oscillation and the tuning of vacuum tube radio circuits they are applicable to any electrical circuit the impedance of which is desired to be controllably varied.

One object of this invention is to provide an improved method of varying the electrical characteristics of a circuit particularly the inductance thereof.

Another object is to provide improved means for varying the relation between the inductance and the resistive component of the impedance of a circuit.

Another object is to provide improved means for varying the phase relation between the currents and the magnetic fluxes in two or more coils placed in mutually inductive relation to one another.

Another object is to provide improved means for changing the inductive component of the impedance of an electrical circuit by changing the resistive component of the circuit.

Another object is to provide improved means for controlling the conditions governing the oscillation of electrical circuits including so-called three element vacuum tubes.

Other objects and novel features of this invention will be apparent from the following specification and the accompanying drawings.

In the drawings:

Fig. 1 shows a wiring diagram of a preferred form of the invention.

Figs. 2 and 3 show two methods of effect-

ing the necessary movements of the contacts upon the resistors, by a single operating means.

Fig. 4 shows a wiring diagram of another form of the device, and Fig. 5 the corresponding method of carrying out the necessary movement of the contact arm on the resistor.

Fig. 6 shows a form of the device in which a simple rheostat is used to vary the self-induction of two mutually inductive coils.

Fig. 7 shows a form of the device in which the mutually inductive coils are connected electrically in parallel and regulation of the division of current between the coils is effected by means of a so-called potentiometer resistance.

Referring to the Fig. 1 the device shown is to vary the impedance between the points 1 and 2 at which points it may be connected in an electrical circuit whose characteristics are to be controlled. The resistances 3 and 4 are connected electrically in parallel by means of the conductors 5 and 6. The inductance coils 7 and 8 are placed in mutually inductive relation to one another, that is the magnetic flux of coil 8 must link with the turns of coil 7. This interlinkage of flux between the coils 7 and 8 should be preferably although not necessarily as great as possible, so that the relation of the coils will be that which is commonly referred to as close coupled. The conductors 9 and 10 (Fig. 1) are adapted to make contact at a variable location on the resistances 3 and 4.

The operation of this device is as follows:

The impedance of the device as measured between the points 1 and 2 is a function of the resistances r_1 , r_2 , r_3 and r_4 and of the self and the mutual inductances of the coils 7 and 8. Let us first consider the case when the conductor 9 makes contact at the extreme right end of resistance 3, adjacent conductor 6; and conductor 10 makes contact at the extreme left end of resistance 4. Under these conditions $r_2 = r_3 = 0$ and r_1 is the entire resistance of 3 while r_4 is the entire resistance of 4. Current entering at the point 2 will pass through coil 8 to the point 11. At this point it will divide into three parts, the greater part going through coil 7 while the remainder divides between the resistances 3 and 4. These three currents recombine at the point 12, and leave the device at the point 1. Let us also assume that the windings of coils 7 and 8 are such that with the

- above described distribution of current the magnetic flux due to the current in coil 7 is added to the flux due to the current in coil 8. This results in a maximum of self-induction 5 between the points 1 and 2 of the device. It will be noted that under these conditions the device substantially comprises two mutually inductive coils in series, one of them namely the coil 7 being electrically in parallel with 10 the resistances 3 and 4. If the resistances 3 and 4 are very large relative to the impedance of coil 7 the resultant inductance between the points 1 and 2 will be given approximately by the expression:

15

$$L = L_7 + L_8 + 2M.$$

Where L_7 is the self induction of coil 7, L_8 is the self induction of coil 8 and M is the mutual inductance of coils 7 and 8.

- 20 Let us now consider the case when the conductor 9 makes contact at the extreme left end of resistance 3, and the conductor 10 makes contact at the extreme right end of the resistance 4. It is apparent that under 25 these conditions the device again substantially comprises a series connection of the mutually inductive coils 7 and 8 with the coil 7 electrically in parallel with resistances 3 and 4. There is, however, an essential difference 30 between the last considered case and that first considered in that the current in coil 7 has been completely reversed. This results in a reversal of the flux in coil 7 so that instead of being added to the flux of 35 coil 8 it is subtracted therefrom. This case therefore gives a minimum of self-induction between the points 1 and 2 the approximate expression for the resultant self-induction being

40

$$L = L_7 + L_8 - 2M.$$

If the coils 7 and 8 be very closely coupled the mutual inductance M approaches the value $\sqrt{L_7 L_8}$.

- 45 If the coils 7 and 8 are so wound that

$$L_7 + L_8 = 2\sqrt{L_7 L_8}$$

- then it is apparent that L would approximate to zero. If the resistances 3 and 4 are 50 high enough to divert a negligible current from coil 7 this condition of zero inductance can be approximated by winding the coils 7 and 8 so that $L_7 = L_8$. In order, however, to 55 compensate for the diversion of current from coil 7 by the parallel resistances 3 and 4 and in order to approach as closely as possible to a zero value of the resultant inductance it is desirable to wind more turns on the coil 7 than are on the coil 8.

- 60 The above discussion shows that a maximum limit of inductance determined by the self and mutual inductances of the coils 7 and 8 may be obtained and a minimum limit approaching zero may also be obtained these 65 limits corresponding to the two diagonally

opposite positions of the contacts on the resistances 3 and 4. Values of inductance intermediate these limits may be obtained by intermediate positions of contacts of conductors 9 and 10 upon their respective resistances 3 and 4. 70

These represent the contact positions at 75 which the magnetic fluxes of coils 7 and 8 change from additive to subtractive relations, with corresponding changes in the resultant inductance of the device.

The changes in inductance above described 80 can all be accomplished in a gradual and continuous manner by a gradual change of the location of the contacts of conductors 9 and 10 upon their respective resistances 3 and 4. 85

The Fig. 2 shows a form of the device in 90 which the above described changes in inductance can be brought about by a single operating means. Referring to Fig. 2 the terminals of the device are shown at 13 and 14. Resistances 15 and 16 are circularly disposed 95 on an insulating base 17 and provided with suitable common terminals 18 and 19. The contact members 20 and 21 are adapted to make contact respectively with the resistances 15 and 16 and are connected to the ends of coil 28 by means of conductors 24 and 25. These contact members 20 and 21 are fixed to the shaft 26 in such a way as to be electrically insulated from one another. The shaft 26 extends rotatably through the base 17 and may be rotated by means of the operating knob 27. The mutually inductive coils 28 and 29 of Fig. 2 correspond to the coils 7 and 8 of Fig. 1. 100

105 The operation of the device is as follows: Current entering at 14 passes through the coil 29, thence to terminal 19 from which it divides between the resistances 15 and 16, and the coil 28, recombining again at terminal 18 and leaving the device at terminal 13. The contact members 20 and 21 being electrically connected to conductors 24 and 25 to which the coil 28 is connected, permit of varying the connections of coil 28 to the resistances 15 and 16 by rotation of the operating knob 27. When contact member 20 is adjacent terminal 19, member 21 is adjacent terminal 18. This position of the contact members corresponds to the case discussed under Fig. 1 in which conductor 9 (Fig. 1) made contact at the right end of resistance 3 and conductor 10 made contact at the left end of 4. It is, therefore, apparent that a 180 degree rotation of the knob 27 effects a gradual change of the resultant inductance between terminals 13 and 14 over a range extending between the limits discussed in connection with Fig. 1. 110

115 Fig. 3 shows another form of the device in 120

which adjustment from maximum to minimum inductance is accomplished by a single operating means rotatable through an angle of approximately 300 degrees. This makes possible a closer adjustment of the inductance than with the device of Fig. 2.

Referring to the Fig. 3 the resistances 30 and 31 circularly disposed on the insulating bases 32 and 33 correspond to the resistances 3 and 4 of Fig. 1. Terminals 34, 35, 36 and 37, 38, 39 are provided to make electrical connection to these resistances. Terminals 34 and 37 and 35 and 39 are interconnected by the conductors 40 and 41 in order to give the connections shown diagrammatically in Fig. 1. The contact members 42 and 43 are electrically insulated from each other and fixed to the common shaft 44. This shaft extends rotatably through the bases 32 and 33 and is rotated by the operating knob 45.

Current entering the device at 46 passes through the coil 48 corresponding to coil 8 of Fig. 1. Thence the current divides between the resistances 30 and 31 corresponding to resistances 3 and 4 of Fig. 1 and a portion goes through the coil 49 corresponding to coil 7 of Fig. 1. The current thus divided is recombined by means of the conductor 40 and leaves the device at the terminal 47.

Fig. 4 shows diagrammatically a somewhat modified device for changing the relation of the magnetic fluxes in two mutually inductive coils and thereby changing the resultant self induction of these coils. In this figure a current entering at terminal 51 passes through the coil 53 and the resistance 52. One end of the coil 54 is connected through a resistance 55 to an intermediate point 57 on the resistance 52, and the other end is connected to a conductor 56 adapted to make contact at a variable location on resistance 52. It is apparent that when the conductor 56 makes contact to the left of the point 57 the current in coil 54 will flow in a direction opposite to that in which it will flow when conductor 56 makes contact to the right of point 57. It is also apparent that the amount of current flowing in coil 54 will be a function of the position of contact of the conductor 56 upon the resistance 52. It, therefore, follows that a variation of the location of the contact of 56 upon resistance 52 will effect a variation both in the magnitude of the magnetic flux of 54 and in the relation of this flux to the flux of coil 53. This variation of flux will result in a variation of the resultant self induction between the terminals 50 and 51.

Fig. 5 shows how the necessary variation of contact described for Fig. 4 may be accomplished by a single operating means.

Referring to Fig. 5 the resistance 58 corresponds to resistance 52 of Fig. 4; coils 59 and 60 correspond to the coils 53 and 54 of

Fig. 4 and resistance 61 corresponds to resistance 55 of Fig. 4. The rotatable contact member 62 fastened to the shaft 63 corresponds to the movable conductor 56 of Fig. 4. It is apparent from Fig. 5 that rotation of the operating knob 64 changes the location of contact of the member 62 over the full range of resistance 58 thus accomplishing the desired changes of resultant inductance of the coils 59 and 60.

Fig. 6 shows another modification for varying the resultant self-induction of two mutually inductive coils by changing the relation of their magnetic fluxes by means of a variable resistance. Referring to Fig. 6 current entering at the terminal 65 passes through the coil 67 and then divides part passing through coil 68, the remainder being shunted around coil 68 through the variable resistance 69. The current leaves the device at terminal 66.

The variable resistance may be of the usual type comprising a contact member 70 bearing on the resistance 69 and rotatable by a knob 71, but preferably should be of the non-inductive type such for instance as described in my co-pending application Serial Number 634,297.

The coils 67 and 68 are preferably very closely coupled and so wound and placed with respect to each other that the magnetic flux of coil 68 opposes the flux of coil 67. Assuming these coils to have the same self-induction and to be perfectly closely coupled the resultant self-induction of the coils will approach zero at the value of the resistance 69 approaches infinity. Also as the value of the resistance 69 approaches zero the resultant self-induction of the coils will approach that of coil 67 alone.

The last described form of the device although the simplest does not give as great a range of variable inductance with two given coils as do the forms of the device shown in the Figs. 1 to 5 inclusive. This is because in the form shown in Fig. 6 the magnetic flux of coil 68 can be either added to or subtracted from the flux of coil 67 but can not be both added to and subtracted from the flux of coil 67 by the movement of a single operating means. In the forms of the device shown in Figs. 1 to 5 inclusive rotation of the operating knob over part of the range adds the fluxes of the two coils and over the remainder subtracts these fluxes. This is obviously a more effective use of the coils although it adds somewhat to the complexity of the resistance portion of the device.

A further form of the device in which the mutually inductive coils are connected electrically in parallel is shown in the Fig. 7. The mutually inductive coils 72 and 73 are so wound and placed with respect to one another that their magnetic fluxes mutually

oppose. Current entering at terminal 75 is divided between the coils 72 and 73 by a so-called, potentiometer resistance 76; and the currents passing through the coils 72 and 73 5 recombine and leave the device at 74. The distribution of current between the coils 72 and 73 determines the resultant self-induction of these coils. When the contact member 77 is adjacent one terminal of the resistance 76 the current will be a maximum though the coil connected to said terminal and the resultant inductance will be substantially equal to that of said coil. At some intermediate position of the contact member 15 77 the current will be so divided between coils 72 and 73 as to make the resultant of their magnetic fluxes approach zero in which case the resultant inductance of the device will be a minimum. This intermediate position 20 will be determined by the relative self-induction of the coils 72 and 73, as well as by their mutual induction. It is, therefore, apparent that rotation of the contact member by means of its operating knob 78 will 25 effect a gradual change of the resultant inductance from a minimum value to the value of the inductance of either of the coils 72 or 73.

In the above described devices it is preferable but not necessary to employ resistances in which a gradual and continuous variation of the location of contact can be accomplished. Resistances of this type are described in my co-pending application 35 Serial Number 634,297.

While several forms of the invention have been shown and described, these have been selected merely for purposes of illustration and not in any way as limiting or restricting 40 the invention which, as will be appreciated, may take a great variety of different forms and arrangement of parts without in any way departing from the spirit or scope thereof as defined in the appended claims.

45 What I claim as new and desire to secure by Letters Patent is:

1. The combination of a pair of inductively related coils, a pair of terminals, one end of one of said coils being connected to one 50 of said terminals, the other end of said coil being connected to the other terminal through a variable resistance and through the other of said coils, whereby the effective resultant inductance between said terminals 55 may be varied.

2. The combination of a pair of inductively related coils, a pair of terminals, one end of one of said coils being connected to one of said terminals, the other end of said 60 coil being connected through a resistance to the other of said terminals, the ends of the other coil being connected to said resistance,

one of the connections being movable along said resistance.

3. The combination of a pair of resistances connected in parallel, a terminal connected to one of the common points of said resistances, a second terminal, a coil connected between the other common point of said resistances and the second terminal, and a second coil having its ends connected to contacts movable on said resistances, whereby the effective self-induction between said terminals may be varied. 70

4. The combination of a pair of inductively related coils, a pair of terminals, one end of one of said coils being connected to one of said terminals, a resistance connected to the other terminal and to the other end of said first mentioned coil, the other of said coils having its ends connected to said resistance, one of the last mentioned ends being connected to said resistance by means of a movable member, means for moving said member, whereby the effective resultant inductance between said terminals may be varied. 75

5. The combination of a pair of inductively related coils, a pair of terminals, one end of one of said coils being connected to one of said terminals, the other end of said coil being connected through a resistance to the other of said terminals, the ends of the other coil being connected to movable members electrically connected to said resistance, and a single control for simultaneously moving each of said members to thereby vary the points of contact with said resistance and the resultant inductance between said terminals. 90

6. The combination of a pair of resistances connected in parallel, a terminal connected to one of the common points of said resistances, a second terminal, a coil connected between the other common point of said resistances and the second terminal, a second coil having its ends connected to movable members electrically connected to said resistances, and a single control means for simultaneously moving said members to vary the points of connection of the ends of said second mentioned coil with said resistances, whereby the effective resultant inductance may be varied. 105

7. A pair of inductively related coils electrically connected to jointly conductively carry a high frequency current, and a variable resistance connected to said coils to vary the distribution of current through said coils, whereby the resultant inductance 110 of said coils is varied.

In witness whereof, I have hereunto subscribed my name.

ERWIN R. STOEKLE.
